UNITED STATES PATENT OFFICE.

RUSSELL J. REANEY, OF OTTAWA, ONTARIO, CANADA, ASSIGNOR TO REANEY LIMITED, OF OTTAWA, CANADA.

MECHANICAL MEANS FOR TRANSMITTING POWER.

Application filed September 29, 1925. Serial No. 59,303.

This invention relates to improvements in a mechanical means for transmitting power, the principal object being to transform a rotary motion into a reciprocatory one and to extend the reciprocation indefinitely.

A further object is to provide a mechanism utilizing cooperating racks that mesh with block encased gear wheels, such blocks and racks being interrelated in a train.

To the accomplishment of these and related objects, my invention resides in the construction, combination and arrangement of parts as shall be hereinafter more fully described, illustrated in the accompanying drawings and pointed out in the claims hereunto appended.

The invention can be most clearly described and most readily understood when reference is had to the accompanying illustrations of the preferred construction in which:

Fig. 1 is an elevation of the train of gear carrying blocks and racks, part being shown in section;

Fig. 2 is a fragmentary plan;

Figs. 3 and 4 are elevations of the rack and block reciprocating mechanism.

Fig. 5 is an alternative form of reciprocating mechanism;

Figs. 6 and 7 are vertical and horizontal sections respectively, as taken on lines 6-6 and 7-7 of Fig. 1; and

Fig. 8 is a section through the lower rack and supporting track.

In this invention for the transforming of rotary motion into reciprocatory and the unlimited extension of the reciprocations, I employ gear wheels encased in blocks or carriages that are connected in a train by racks, meshing with the gear wheels, that are also mounted on the blocks. The series or train of interconnected blocks are arranged in alignment and all ride on a main rack, meshing with the gears, that is reciprocated. The first block in the series carries no rack but the encased gear meshes with the rack from the second block whose enclosed gear receives in turn the rack mounted on the third block and so on.

The mechanism producing the reciprocations of the train of gear blocks and of the main rack which are opposed, differs depending on the nature of the source of power: If rotary, a shaft with collars riding

on reversed threads is used and the shaft oscillated by a segmental crown gear acting on a pair of spaced pinions keyed to the far end of the threaded shaft—or if reciprocatory and paralleling the train, by fixed or rigid and pivoted lever arms that connect respectively with the end gear block and main rack.

Referring more particularly to the drawings wherein like characters indicate like parts throughout the several views, 10 is a suitable base on which a track 11 is positioned to support a rack 13 that is adapted to reciprocate horizontally. A number of blocks 14 straddle this rack within each of which is enclosed a gear wheel 15 that meshes with the rack 13 and rides thereon supporting the block in this way. A channel 16 is cut through the blocks near the top from end to end and is so disposed with relation to the enclosed gear that a rack member 17 designed to pass therethrough may contact with the said gear.

The rack 17 is carried by that block 14 immediately behind the block encasing the gear wheel with which it contacts and is applied to the block by fastenings 18 on each side, the rack piece being bifurcated and formed to laterally engage both sides of the block as shall be more fully described.

It will thus be seen that the train of interconnected blocks 14 and the main rack 13 are both adapted to reciprocate horizontally and so the maximum of efficiency is to be obtained from this mechanism by causing these parts to reciprocate in opposite directions. To accomplish this I provide a shaft 19 an end of which is threaded left for a space and then threaded right as at 20^a and 20^b respectively and to these reverse threads are applied collars 21 and 22 from the former of which a standard extends to connect with the reciprocable rack 13 while an arm spaced from and paralleling the axis of the latter is fixed to the block 14 on the near end of the train. The end of the shaft remote from the threads carries a pair of spaced pinions 23 that mesh with opposite sides of the same face of a segmental crown gear 24 supplying the power in this instance. The crown however is toothed through less than a half of its circumference so that on turning opposite rotations are imparted to the shaft 19 by its meshing with first one pinion and then the other. At suitable locations throughout

its length the said shaft is supported by bearings 25 on standards 26.

As is obvious this type of reciprocating mechanism can only be employed when the power is being supplied in the rotary form, I have included a modification to operate the device when a reciprocating source is to be utilized. This, as shown in Fig. 5, comprises a shaft 27 reciprocating in a plane parallel with the transmission, a rigid arm 28 therefrom fixed to the end block 14 and a centrally pivoted lever 29 connected to the end of the main rack 13, the pivoted connection on each end thereof including a pintle receiving slot.

The racks 13 and 17 to which reference is made in the preceding will preferably be in the form of channels between whose upright sides little rollers 30 are arranged transversely.

In the case of the rack members 17 the base of the channel is partially removed to form a fork that bridges the block to which it is applied and fastened thereto as described. The lower or main rack, having to reciprocate on the track 11 is recessed to receive the same by having the bottom of the channel raised between the arms thus forming a double thickness of side for a part thereof and then having the lowermost edges bent inwardly and securely and snugly embracing the rail. Friction is reduced by the insertion of roller bearings 31 between the underside of the channel base and the track.

In operation, when the required number of gear carrying blocks or elements have been arranged in line and means for oppositely reciprocating the blocks and main rack have been connected, the end block, remote from that receiving the reciprocations is moved back and forth a distance proportionate to, but many times greater than the first block e. g., if the first block is advanced one inch and the main rack moved the same distance in the opposite direction, the second gear block is advanced three inches the third six inches and so on for it will be observed that if the main rack was fixed and the first block advanced one inch the second block would move a like distance without the action of the gear and rack but with this the gear is rotated by contact with the fixed lower rack and this rotation advances the rack member fixed to the second block thereby drawing the said block up another inch, making a total of two inches: The ratio being as $a:2(a):2(2a):2(4a)$ etc.; while the opposite reciprocation of the main rack still further advances the blocks, excepting the first, in the proportion of $b:2b:3b$ etc. This movement in like increasing relation is transmitted to each successive block element applied to the train so that the multiplying of the movement may be carried out to any desired extent.

From the foregoing description taken in connection with the accompanying drawings, it will be manifest that a mechanical means for transmitting power is provided which will fulfill all the necessary requirements of such a device, but as many changes could be made in the above description and many apparently widely different embodiments of my invention constructed within the scope of the appended claims without departing from the spirit or scope thereof, it is intended that all matters contained in the said accompanying specification and drawings shall be interpreted as illustrative and not in a limited sense.

What I claim as new and desire to secure by Letters Patent is:—

1. A mechanical means for transmitting power comprising a train of meshing gear and rack elements, said gears being encased in individual carriages to each of which, excepting the first in the train, is applied a rack adapted to mesh with the gear immediately preceding.

2. A mechanical means for transmitting power comprising a plurality of gears, each encased in an individual carriage, said carriages being arranged in alignment and a plurality of racks, one applied to each of said gear carriages with the exception of the first of said carriages, each adapted to mesh with the gear in the carriage immediately preceding the carriage to which it is applied.

3. A mechanical means for transmitting power comprising a plurality of gears, each encased in an individual carriage, a reciprocating rack on which said carriages are aligned and with which said gears are adapted to mesh, the carriages being supported thereby and individual racks mounted on the said carriages each meshing with the gear in the carriage immediately preceding.

4. In a mechanical means for transmitting power the combination with a base, a track rigidly secured thereto, a rack mounted and adapted to reciprocate on said track, a plurality of carriages arranged in alignment on said track straddling the same, a gear wheel disposed in each of said carriages adapted to ride on the said rack and support the carriage thereby and means for interconnecting the said train of carriages.

5. In a mechanical means for transmitting power the combination with a base, a track rigidly secured thereto, a rack mounted and adapted to reciprocate on said track, a plurality of carriages arranged in alignment on said track straddling the same, a gear wheel disposed in each of said carriages adapted to ride on the said rack and support the carriage thereby and means for interconnecting the said train of carriages so that on movement of the said rack the same are caused to move in progression.

6. In a mechanical means for transmit-

- ting power the combination with a base, a track rigidly secured thereto, a rack mounted and adapted to reciprocate on said track, a plurality of carriages arranged in alignment on said track straddling the same, a gear wheel disposed in each of said carriages adapted to ride on the said rack and support the carriage thereby and means for interconnecting the said train of carriages so that on movement of the said rack and carriages the latter are caused to move in a combination of progressions.
7. In a mechanical means for transmitting power the combination with a base, a track rigidly secured thereto, a rack mounted and adapted to reciprocate on said track, a plurality of carriages arranged in alignment on said track straddling the same, a gear wheel disposed in each of said carriages adapted to ride on the said rack and support the carriage thereby and means for interconnect-
- 10

ing the said train of carriages so that on movement of the said rack and carriages the latter are caused to move in a combined harmonic and arithmetic progression.

25

8. In a mechanical means for transmitting power the combination with a base, a track rigidly secured thereto, a rack mounted and adapted to reciprocate on said track, a plurality of carriages arranged in alignment on said track straddling the same, a gear wheel disposed in each of said carriages adapted to ride on the said rack and support the carriage thereby and interconnecting racks applied to the said carriages for cooperation with the gears and designed to convey to each successively the combined progress of those preceding.
